PULLING-OVER MACHINE

Eric A. Holmgren and Harry B. Patten, Beverly,
Mass., assignors to United Shoe Machinery Cor-
poration, Flemington, N. J., a corporation of
New Jersey

Application July 10, 1942, Serial No. 450,422

43 Claims. (Cl. 12—4)

This invention relates to machines for use in the manufacture of shoes and more particularly to machines for making stitchdown shoes, and is illustrated herein as embodied in a machine for pulling over the uppers of stitchdown shoes.

In the manufacture of shoes of the type referred to, the lower portion of the upper is turned outwardly away from the last upon which the shoe is to be made to provide an outturned margin or flange, and the upper is permanently attached to a mid-sole or other sole member on the last by securing this outturned margin to the portion of the sole member which projects beyond the periphery of the last bottom, the attaching means usually consisting of fastenings, such as stitches, located close to the last in the angle or crease formed by the side portion of the last and the outwardly extending margin of the upper.

Before the upper and sole member can be properly attached to each other by the lasting stitches, however, they should be assembled in proper relation on the last and the upper should be pulled over and secured in a suitable manner to the projecting sole member in order that the upper may be held in pulled-over position on the last until the permanent attaching means can be inserted.

Machines for pulling over stitchdown shoes or machines provided with special apparatus or attachments for performing this operation are not usually arranged also to secure the upper in pulled-over position on the last by inserting fastenings such as staples or the like, and those which are so arranged usually involve departures from the more common methods of making stitchdown shoes followed or employed by most manufacturers. Consequently, it has been customary heretofore in many factories for the operators to perform this relatively important operation by hand with hand or bench pincers or grippers and with the aid of a machine arranged to insert single fastenings, such as staples, through the upper and sole member. In carrying out the pulling-over operation by this process, the operator assembles an upper and a sole member on a last in the usual manner and uses the hand or bench grippers to pull over the upper at one side of the shoe and he inserts a fastening or staple through the upper and sole member on that side after it has been pulled over. He then pulls over the other side of the upper with the hand grippers and inserts a fastening in that side also.

It will be apparent that the above procedure is 55 wardly of the last by such movement. At the

apt to be unsatisfactory today, when speed, economy and good workmanship are essential, because in many instances shoes pulled over by this method are not pulled over uniformly or evenly on both sides and, consequently, the uppers are frequently displaced widthwise of the last which results in poorly constructed or defective shoes. Moreover, the uppers are not always pulled over the last as tightly as they should be, especially at the forepart, when the upper has been pulled over one side at a time by this hand method. In addition, the hand method obviously involves more time and labor than would be required in performing the same operation, including the insertion of fastenings, by machine.

An object of the present invention is to provide an improved machine for use in the manufacture of shoes which is adapted to perform a pulling-over operation on shoes, such as stitchdown shoes, the machine being particularly arranged to perform this operation efficiently, rapidly and with better and more uniform results than have been possible heretofore by the methods referred to.

To this end the invention provides, in accordance with one feature, an improved machine provided with a support for receiving a last, the last having an upper mounted thereon together with a sole member which projects beyond the last bottom, the machine being provided with further means or mechanisms at opposite sides of the support for gripping the opposite margins of the upper at the forepart of the last and holding these margins in an outturned position over the projecting sole member. Further means is also provided on the machine for effecting relative movement of the shoe support and the gripping mechanisms heightwise of the last to cause the upper to be pulled over the last and, in accordance with another feature of the invention, mechanisms are provided for inserting metal fastenings, such as staples, through the projecting sole member and upper margins at opposite sides of the last to secure the upper in pulled-over position on the last.

As illustrated herein, the shoe support is arranged to move heightwise and lengthwise relatively to the gripping mechanisms in order to accomplish the pulling-over operation, the grippers remaining stationary during this movement so that the upper at opposite sides of the last will, in effect, be pulled downwardly and for-

termination of the relative movement, the grippers are arranged to hold the opposite margins of the upper in an outturned position overlying the projecting margin of the sole member. In the present embodiment of the invention, as illustrated herein, the fastenings may comprise ordinary preformed staples supplied, for example, from a usual staple strip or bar and, in accordance with a further feature of the invention, the fastening inserting mechanisms are arranged to insert the staples upwardly in an inverted position so that they will pass first through the projecting sole member and then through the overlying margins of the upper, the staples being thereafter clinched by the mechanisms against the exposed surface of the upper. As illustrated, the staples are inserted simultaneously at the opposite sides of the last and are preferably located by the inserting means at predetermined distances from the last bottom in the angle or crease formed by the last and the outturned margins of the upper.

In order to insure that the stitchdown upper will be pulled over the last smoothly and tightly at all portions thereof, the machine is also arranged to cause the opposite side portions of the upper to be moved inwardly toward the support at a predetermined time in the cycle of operations of the machine to press the upper against the sides of the last, this movement taking place after the pulling-over operation has been performed but before the fastenings have been inserted. As herein illustrated, the pressing operation is performed automatically by the machine by causing the opposite margins of the upper and the projecting sole member to be first clamped between the fastening inserting mechanisms and stationary members or anvils provided for clinching the staples, the opposite sets of mechanisms being thereafter caused to move inwardly toward the support with a yielding action while remaining in clamping engagement with the upper and sole member. In this way, the upper is pulled over the last tightly and evenly and the fastenings are inserted while the upper is held in such position, the position of the fastenings, as indicated above, being determined or controlled by the fastening inserting mechanisms.

In addition to the foregoing, the present invention provides various other novel features and arrangements of parts among which are improved means for adjusting the gripping and fastening inserting mechanisms widthwise and angularly with respect to the support to adapt them for operating upon shoes of different styles and sizes, the widthwise adjusting means, as herein illustrated, comprising a single member in the form of a manually operated screw for adjusting the mechanisms at both sides of the support simultaneously toward or away from the support. The means for obtaining an angular adjustment of the mechanisms are separate or individual for each set of mechanism so that they may be adjusted independently of each other into different angular positions with respect to the support in accordance with the size or style of the shoe being operated upon. As herein illustrated, the single means for initially adjusting the gripping and fastening inserting mechanisms toward or away from the support is arranged so that, while it accomplishes the same functions as the means for automatically moving these mechanisms inwardly to press the upper yieldingly against the last, it does not interfere with the operation of

this automatic means but, on the contrary, assists said means in producing this inward movement of the mechanisms, the automatic means, however, operating independently of the operation of the single adjusting means.

With the above and other objects and features in view, including means for releasing the grippers after the upper has been clamped but before it is pressed against the last, and improved means for actuating the different operating mechanisms of the machine in proper timed relation to each other, the invention will now be described in detail in connection with the accompanying drawings and will thereafter be pointed out in the claims.

In the drawings,

Fig. 1 is a front elevation of a machine embodying the present invention with the lower or base portion of the machine broken away;

Fig. 2 is a vertical section through the central portion of the machine with some of the mechanism shown in Fig. 1 omitted;

Fig. 3 is a horizontal section taken on the line III—III of Fig. 1;

Fig. 4 is a sectional detail taken on the line IV—IV of Fig. 3;

Fig. 5 is a front elevation of a part of the operating mechanism located on the right-hand side of the machine in Fig. 1, the mechanism being shown on an enlarged scale and partly in section;

Fig. 6 is a sectional view taken on the line VI—VI of Fig. 5;

Fig. 7 is a sectional detail view taken on the line VII—VII of Fig. 5;

Fig. 8 is a plan view of the work engaging portions of the operating mechanism of the machine operating upon a shoe;

Fig. 9 is an enlarged detail view of the right-hand operating mechanism at an intermediate stage of its operation upon the shoe, the last and shoe being shown in section;

Fig. 10 is a view similar to Fig. 9 at a later stage in the operation of the mechanism;

Fig. 11 is another view similar to Fig. 9 at a still later point in the operation of the mechanism but with the gripping mechanism removed to illustrate the fastening inserting mechanism more clearly;

Fig. 12 is a section taken on the line XII—XII of Fig. 11 showing a fastening being inserted and clinched in the work piece or shoe; and

Fig. 13 is a plan view of the forepart of the shoe after the operations performed by the machine have been completed.

The illustrated machine is provided with an upstanding base or frame 20 supported on four legs and extending upwardly a convenient distance for an operator to present the work to the machine. The upper end of the base 20 is substantially rectangular in plan view and has short vertical studs 22 secured to it by screws adjacent to its four corners, these studs supporting on their upper ends a horizontal plate or table 24 which carries the operating mechanisms of the machine. The plate 24, as illustrated in Figs. 1 to 3, inclusive, is much longer than it is wide and is positioned with its lengthwise dimension extending forwardly and rearwardly of the machine.

On the forward portion of the table 24 are mounted two upstanding U-shaped brackets 26, 28 (Figs. 2 and 3) secured to the table by screws

30. Pivoted between the ears of the bracket 26 on a pin 32 is a lever 34 which forms the for-

ward link of a toggle, the other link of which is provided by a second lever 36 pivotally mounted on a pin 38 between the ears of the other U-shaped bracket 28. The toggle levers 34, 36 are pivotally connected to each other by a pin 40 extending through slots formed in the adjacent ends of said levers, the toggle lever 34 being bifurcated at its inner end to straddle the lever 36. The pin 40 is secured in the upper end of a treadle rod 42 which passes downwardly through a hole in the table and, at its lower end (Fig. 1), is pivotally connected to a foot treadle 44 fulcrumed between fixed collars 45 on a long horizontal shaft 46 extending widthwise of the machine and rotatably mounted in bearings formed on the lower ends of the two rearward legs of the base 20, the treadle 44 being normally maintained in its elevated position by a tension spring 48 extending between the treadle and a fixed upper portion of the base or frame.

Pivotally mounted on a pin 49 on the forward end of the toggle lever 34 is an upwardly extending arm 50 and pivotally mounted on a pin 51 on the rearward end of the other toggle lever 36 is a similar arm 52, these two arms, as shown in Fig. 2, being parallel and having their upper ends bifurcated to provide ears between which is pivotally mounted, by means of pins 54 and 55, a long narrow T-shaped plate 56, the upper surface of which is maintained in a horizontal position by reason of the parallel arms 50, 52, the plate 56 constituting the shoe supporting member of the machine. A heel block 60 is removably secured on the forward portion of the shoe support 58 by a pair of pins 62 projecting from the lower surface of the block and arranged to enter any of a plurality of sets of holes 64 spaced from each other lengthwise of the support, thereby permitting the heel block to be readily removed and adjusted lengthwise of the support to accommodate shoes of different lengths or sizes.

The inner or rearward portion of the support 58 has secured thereon a pair of small rectangular blocks 66, 68 (Figs. 2 and 8) which serve as toe rests for supporting the toe end of the shoe, the blocks 66, 68 being located in substantial alignment with the opposite edges of the plate by dowel pins and being secured respectively thereto by screws 70 and 72. Mounted on the inner end of the support 58 is a toe gage 74 which is secured to a rectangular block 76 on the support by a pair of screws 78, the gage being adjustable lengthwise of the support to adapt it for shoes of different sizes by means of a horizontal adjusting screw 80 threaded into the block 76 and provided with a knurled head 82. At its rear end the toe gage 74 has a downwardly extending ear 84 which is bifurcated to engage a circumferential slot in the screw 80 so that, when the clamping screws 78 are loosened and the adjusting screw is rotated, the gage may be adjusted into the desired position lengthwise of the shoe support 58, the clamping screws 78, as shown in Fig. 8, passing through elongated slots 86 in the gage to permit the adjustment to be made.

The forward portion of the toe gage 74 (Figs. 2 and 8) extends over the toe rests 66, 68 in position to engage the toe end of the last in the shoe while permitting the projecting portion of the sole to pass under the gage and permitting the marginal portions of the upper to extend over the gage and toe rests. As illustrated in Figs. 2, 8 and 9, the forward or operative end of

the toe gage comprises a relatively wide vertical surface 88 extending transversely of the support 58. Fig. 8 shows a shoe mounted on the shoe support with its heel end resting on the heel block 60 and its toe end engaging the toe rests 66, 68, this figure illustrating also how the toe gage 74 locates the last lengthwise of the support in position for the shoe to be operated upon by the operating instrumentalities of the machine.

The inner toggle lever 36 (Fig. 2) has an arm 90 projecting upwardly above its pivot 38 and pivotally connected to this arm by a pin 92 are a pair of long links 94 which extend forwardly and are pivotally connected at their front ends to the upstanding arm 50 by a pin 96 arranged to be inserted in any one of a series of holes 98 formed heightwise in the arm 50 so that the front ends of the links 94 may be adjusted heightwise of the arm. The forward toggle lever 34 has a pair of adjustable stop screws 100 and 102 threaded thereon at opposite sides of its pivot 32, the screw 100 determining the broken or inoperative position of the toggle by engagement with the plate 24, as shown in Fig. 2, and the rearward screw 102 determining the straightened or operative position of the toggle. The extent of operative movement of the toggle levers about their pivots, therefore, may be varied by adjustment of the stop screws in the lever 34.

Depression of the treadle 44 moves the rod 42 downwardly to straighten the toggle levers 34, 36 and to swing the opposite ends of these levers upwardly, thereby moving the parallel arms 50, 52 upwardly to elevate the shoe support or plate 56. The links 94 are moved forwardly, or toward the left in Fig. 2, during this action by the arm 90, so that, as the parallel arms 50, 52 move upwardly, they are caused to swing forwardly about their pivots a distance depending upon the adjusted position of the links 94 on the forward arm 50. Consequently, a shoe mounted on the support 58 will, upon depression of the treadle 44, be moved upwardly with the support simultaneously in a heelward direction as the support is moved forwardly toward the operator a predetermined distance relatively to the rest of the mechanism of the machine.

In order to maintain the treadle 44 depressed after it has been operated, a pair of latches 104, 106 are provided at the front end of the table 24, these latches being pivoted on a horizontal pin 108 mounted in a forwardly extending projection on the table. Springs 110 and 112 (Figs. 2 and 3) are connected to the latches and to pins 114, 116 in the U-shaped bracket 26 and tend normally to swing the latches rearwardly, as viewed in Fig. 2, against the lower pivot pin 49 for the arm 50. When the pin 49 is elevated, through depression of the treadle, the latches drop under the pin and lock the mechanism in its operated position with the support 58 in its elevated and forward position.

If it is desired to inspect the shoe before the treadle has been completely depressed, for example, to insure that the shoe has not been displaced on the support, one of the latches may have its notched portion located slightly below that of the other latch which will permit the operator to release the treadle to inspect the work after the lower latch has moved under the pin 49 without causing the mechanism to return to its open or inoperative position. As illustrated in Fig. 2, the latch 106 is slightly lower than the latch 104. The latches 104, 106 are provided re-

spectively with handles 118, 120 whereby they may be released manually to return the shoe support to its lower position when the operation has been completed or, if desired, to return the support if the shoe has become displaced before the treadle has been fully depressed.

The action of the treadle mechanism in elevating the shoe support 58 and simultaneously moving it forwardly toward the operator, as described above, is utilized in the machine for performing a pulling-over operation on the upper of a stitch-down shoe, this action taking place relatively to further mechanism of the machine, part of which is adapted to grip and hold the upper at opposite sides of the forepart of the shoe and thereby to cause the upper, in effect, to be pulled downwardly and forwardly over the last through the movement of the shoe support 58 relatively to said further mechanism. The gripping mechanism referred to is best shown in Figs. 1, 2 and 8 to 10, inclusive, and since this mechanism is practically identical at opposite sides of the support, only the mechanism at the right-hand side of the machine, as viewed in Fig. 1, need be described in detail herein.

The gripping mechanism is arranged to engage the upper a short distance rearwardly of the tip line of the shoe and comprises an upper gripper 122 of substantial width pivoted on a pin 124 mounted between side walls projecting inwardly from a carrier member 126 which, in turn, is secured by pins or screws 128 to a thick plate fastened to a vertical supporting plate 130, the latter plate being arranged for angular adjustment relatively to the shoe support 58, as will be later explained. The upper gripper 122 is provided on its inner end with a slot or groove 131 with which a lower gripper of the mechanism cooperates to grip the shoe upper in a yielding manner which permits the upper to slip under excessive tension, as will be pointed out, the gripper 122 being arranged to yield upwardly about its pivot 124 under sufficient pressure by reason of a relatively heavy compression spring 132 (Fig. 1) mounted in a cylindrical opening formed in the carrier member 126 and normally pressing upwardly against an enlarged lower end on an adjusting screw 134 threaded through an outwardly extending arm 136 of the gripper 122. A threaded collar 138 is provided for locking the screw 134 against movement in the arm 136 after the screw has been adjusted to produce the required tension of the spring 132. The spring urges the outer arm 136 of the gripper 122 upwardly about its pivot 124 and normally maintains the gripper in a stationary operative position which is determined by an upstanding projection or lug 140 on the gripper engaging a fixed stud 142 extending between the opposite side walls of the carrier 126.

The lower jaw of the gripping mechanism comprises a substantially L-shaped gripper 144 having a single transverse rib or tooth 146 on its lower arm for cooperating with the groove 131 in the gripper 122, and provided on its upper arm with a pair of upwardly extending ears 148 (Figs. 2 and 9) which straddle the upper gripper and are pivotally mounted on fixed pins 150 secured by set screws in the opposite side walls of the carrier member 126. The gripper 144 is slotted at its outer portion to receive the inner end of a toggle link 152 pivotally connected to the gripper by a pin 154. The other end of the link 152 is connected to an outer toggle link or lever 156 by a pin 158 (Fig. 1), the link 156 being

longer than the link 152 and being pivoted about midway of its length by a pin 160 to ears depending from the carrier member 126. The outer end of the toggle lever 156 is pivotally connected by

5 a pin 162 to a treadle rod 164 which extends downwardly and is yieldingly connected at its lower portion to a treadle lever 166 mounted on the shaft 46 and rigidly secured to said shaft by a pin 168 so that movement of the treadle 10 166 rotates the shaft in its bearings on the machine.

The yielding connection between the treadle rod 164 and the treadle 166 is provided, as herein illustrated, by a vertical plate 170 rigidly secured 15 to the treadle lever and carrying at its upper portion a block 172 rotatably mounted in the plate by a pin. The treadle rod passes through a hole in the block 172 and has a compression spring 174 surrounding it below the block, the spring being adjustably retained on the rod by a lock nut 176. Above the block 172, the treadle rod has secured to it by a set screw a collar 178 which is normally urged downwardly against the block by the spring 174 to locate the treadle rod 20 in a predetermined elevated or inoperative position, as shown in Fig. 1. A tension spring 180, extending between the treadle and a fixed portion of the frame, maintains the treadle normally 25 in its elevated position which is determined by its engagement with an adjustable stop screw 182 threaded through a horizontal arm 184 rigidly secured to the frame. When the treadle 166 is depressed to operate the grippers through the toggle mechanism described above, the treadle rod 164 will be lowered yieldingly through the action of the spring 174 which will be compressed 30 between the block 172 and the lock nut 176. When the treadle is released and is elevated by the spring 180, it raises the treadle rod positively 35 to inoperative position by the engagement of the block 172 with the fixed collar 178, the spring 174 expanding to maintain the collar against the block.

As pointed out above, the shaft 46, upon which 40 both treadles are mounted, is rotated when the gripper treadle 166 is depressed because the latter is pinned to this shaft. The shaft 46 extends across the entire machine and has mounted on its opposite end, as viewed in Fig. 1, a forwardly 45 extending lever 186 pinned to the shaft like the treadle 166 and provided with a rotatable block 188 through which a vertical rod 190 passes, a spring 192 being provided on the rod below the block 188 to urge the rod downwardly and maintain a fixed collar 194 normally against the block. The upper end of the rod 190 is pivotally 50 connected by the pin 162 to the toggle mechanism for operating the lower gripper jaw 144 of the left-hand gripping mechanism which, as previously 55 explained, is substantially the same as the gripping mechanism described above except that it is located in an opposite or reverse position.

Depression of the gripper treadle 166, therefore, straightens the toggles 152, 156 on both sets of gripping mechanisms and swings the lower grippers 144 upwardly about their pivots 150 into gripping relation with the normally stationary upper grippers 122, the latter, however, as pointed out above, being arranged to yield under sufficient pressure to compensate for differences in the thicknesses of the upper materials of the shoes operated upon.

In mounting a stitchdown shoe on the support 70 58 prior to the operation of the grippers, the

upper is first mounted on the last and the sole member is secured temporarily to the last bottom in any usual manner as, for example, by a few tacks inserted along the central portion of the sole. The heel end of the shoe is placed on the heel block 68, which will have been adjusted into the proper lengthwise position for the shoe being operated upon, and the forepart of the shoe will rest on the fixed toe rests or abutments 66, 68. The toe end of the last will be moved into engagement with the toe gage 74 which, if necessary, will have been adjusted longitudinally as much as required for locating the shoe in a proper position lengthwise of the support.

It is desirable to position the shoe widthwise as well as lengthwise on the support 58 and, accordingly, the machine is provided with a pair of side gages arranged to engage the opposite edge faces of the sole member adjacent to its toe end and to position the forepart of the shoe laterally or widthwise of the support so that it will be located substantially central with respect to the opposite gripping mechanisms which are located somewhat rearwardly of the tip line of the shoe.

These side gages, as illustrated in Figs. 1, 5, 8 and 9, comprise a pair of long plates or blades 181 secured by screws 183 in horizontal slots 185 formed in the forward surfaces of the supporting plates 130, the gages having their inner ends rounded over for engaging the opposite edges of the sole member adjacent to its toe end and being adjustable in the slots 185 widthwise of the shoe by means of horizontal slots 187 in the supporting plates 130 through which the screws 183 pass. As shown in Figs. 8 and 9, the side gages 181 are located a short distance above the top surfaces of the toe rests 66, 68 so that they will be in position to engage the opposite edge faces of the sole member mounted on the toe rests. When the support 58 moves upwardly, as indicated diagrammatically in Fig. 9, the sole is moved out of engagement with the side gages which are stationary on the plates 130.

After a stitchdown shoe with its sole member secured to the last bottom has been mounted on the support 58 and has been correctly positioned lengthwise by the toe gage 74 and widthwise by the side gages 181, the forepart of the upper extends outwardly away from the last at each side of the shoe and is in position to be engaged and held by the grippers, as illustrated in Figs. 8 to 10, inclusive. The operator then depresses the treadle 166 to operate the gripping mechanisms.

After the grippers at both sides of the shoe have gripped the upper, it is desired to maintain them in gripping relation with the upper without holding the treadle 166 depressed, so that the operator will be free to perform other functions in operating the machine. To this end, the left-hand supporting plate 130, as viewed in Fig. 1, has a horizontal pin 196 rotatably mounted therein upon the forward end of which is secured a latch 198 which extends downwardly and is provided with a notch or shoulder 200 at its lower end, the latch having a split hub surrounding the pin 196 and being rigidly secured thereto by a clamping screw 202.

On the inner end of the pin 196, behind the plate 130, is secured by a tapered pin 204 a laterally extending member 206 provided with an inner arm 207 and a lower arm 209 to which is secured a tension spring 210, the other end of the spring being secured to a pin 211 fastened in the plate 130. The spring 210 tends normally to urge the member 206 in a clockwise direction, as seen in

Fig. 1, to hold the inner arm 207 against a stop pin 209 mounted in the plate 130, thus holding the latch 198 in a vertical position adjacent to the pin 196 which connects the toggle lever 156 to the vertical rod 190 of the left-hand gripping mechanism. When the treadle 166 is depressed to straighten the toggles 152, 156 at the opposite sides of the machine and thereby to close the grippers, the pin 196 is moved downwardly and swings the latch to the right until the pin is below the shoulder 200, at which point the latch snaps over the pin to prevent it from moving upwardly again until the latch is released, thereby locking the grippers in their operated position and holding the treadle 166 depressed. An upwardly extending arm 212 is provided on the latch for releasing it manually, if desired, and further connections are provided between the member 206 and other mechanisms of the machine for releasing the latch automatically during the operation thereof, these connections being more fully described hereinafter.

In the normal operation of the mechanism thus far described, the operator, after mounting a shoe on the support 58, depresses the treadle 166 to operate the grippers simultaneously at both sides of the support, thereby gripping the opposite sides of the upper somewhat rearwardly of the tip line, as shown in Fig. 9. He then depresses the central treadle 44 to effect the pulling-over operation on the shoe, as described above, through the upward and forward movement of the shoe support 58 relatively to the grippers, the operator holding the shoe in position on the support during this relative movement to prevent it from becoming displaced on the support.

Before describing these operations in further detail, however, or describing the fastening inserting operation which follows them, it should be explained that, before the grippers are operated, they and other mechanisms associated with them, including the fastening inserting mechanism above referred to, have to be adjusted sometimes with respect to the shoe support 58 in order to accommodate or adapt the mechanisms for operating upon shoes of different shapes and sizes. Accordingly, the machine is provided with mechanism for adjusting the grippers and associated mechanisms at opposite sides of the support 58 into different positions relatively to the support and to the shoe mounted thereon, so that the grippers and fastening inserting mechanism will be located in the proper widthwise positions and at the proper angles for operating upon a shoe of the particular size and shape of that on the support.

Since the adjusting mechanism referred to moves the opposite fastening inserting mechanisms of the machine, including the clinching anvils, as well as the gripping mechanisms into proper widthwise and angular relation to the support 58 to adapt them for operating upon shoes of different shapes and sizes, a description of the adjusting mechanism will be left until after the fastening inserting mechanism has been described.

The fastening inserting mechanism comprises a stationary clinching anvil 214 at each side of the machine located beside the upper gripper 122 but positioned inwardly thereof, as viewed in Fig. 1, these anvils being so arranged with respect to a shoe on the support that they will clinch the fastenings just rearwardly of the tip line of the upper. As illustrated in Fig. 5, the anvil 214 for the right-hand mechanism is provided with

clinching cavities 216 and has a cylindrical shank 218 mounted in a hole 220 formed at a proper angle in a relatively thick plate 222 interposed between the carrier member 126 and the supporting plate 130, the plate 222 being fastened to the supporting plate by a screw 224 and a pin 226, and the anvil being adjustably secured in the plate 222 by a binding screw 228. As shown in Fig. 8, the opposite anvils 214 preferably extend inwardly slightly beyond the grippers 122 in order to locate the clinching cavities 216 in predetermined positions relatively to the edge of the bottom of the last in the shoe or, in other words, in definite lateral positions relatively to the angle or crease formed in the upper where its marginal portion is bent outwardly to overlie the projecting margin of the sole member, as shown in Figs. 9 to 11. The position of the fastening member or staple which is to be inserted in the upper at the opposite sides of the shoe, just rearwardly of the tip line, is rather critical and, accordingly, the anvils 214 have been made adjustable in the plates 222 so that they may be varied as may be necessary to insure the correct positioning of the staples widthwise of the shoe. As illustrated in Figs. 11 and 13, the staples are located in the upper relatively close to the angle or crease formed by the outturned flange or margin of the upper but are nevertheless spaced from this crease a sufficient distance to permit the permanent lasting stitches to be inserted inwardly of the staples in the stitchdown lasting operation.

The fastenings or staples utilized in the present machine are the usual type of preformed wire staples having two parallel legs joined by a bar portion, one of these staples being shown inserted and clinched in Fig. 12. The machine is arranged to receive the preformed staples from the well-known staple strips in which the staples are secured together in side by side relation by adhesive or otherwise to produce a long U-shaped bar or strip which may be inserted bodily in a staple magazine provided in the machine and fed as a unit toward driving position where the staples are broken off the strip one by one by the driving mechanism and inserted in the work piece.

As illustrated in Figs. 1, 5 and 7, the magazine for holding the staple strip comprises a pair of long, L-shaped side plates 230 spaced from each other by a bar member 232 and inclined downwardly at a small angle to the horizontal from their inner to their outer ends, the assembly being supported near its outer portion, a short distance forwardly of the plate 130, by a yielding pivotal connection 314 which will be described hereinafter. The L-shaped side plates 230 and bar member 232 form the body portion of the magazine (Figs. 5 and 7), the side plates being secured to the bar by pins or rivets 234 located at spaced intervals along the members. The bar 232 is reduced in width at its lower portion 236, as shown in Fig. 7, to provide an opening or guideway 237 in the magazine for receiving the staple strips which are inserted in an inverted position or with their legs extending upwardly, the strip being indicated in Fig. 5 by the numeral 238. Mounted for sliding movement in the space or guideway 237 is an elongated U-shaped staple feeding member 240, the forward or left-hand end of which, as viewed in Fig. 5, engages the outer end of the staple strip 238. The U-shaped feeding member 240, as shown in Fig. 7, fits the staple guideway of the magazine and is arranged to slide freely therein, the outer end of the feed-

ing member being provided with a downward projection or fin 242 which enters a vertical slot 244 extending lengthwise of a U-shaped block 246, the projection 242 being notched on its rearward edge to engage a pin 248 carried by the block. Mounted in the inner or forward end of the block 246 is a transverse pin 250 to which is secured the outer or free end of a long, coiled spring 252 composed of flexible material such as spring steel in the form of a ribbon, the inner end 254 of the spring being inserted into a transverse slot 255 extending through a short horizontal shaft 256 (Figs. 5 and 6). The spring 252 is wound around the shaft 256 with a sufficient number of turns or coils 258 to cause the spring to exert enough tension on the block 246 to urge it constantly inwardly of the magazine and, through the feeding member 240, to feed the staple strip 238 inwardly toward the fastening inserting mechanism.

Fastened to the bottom of the U-shaped block 246 is a thin plate or strap 260 having a rearwardly extending end portion 262 which is bent downwardly at its outer end to provide a hook 264 which the operator may engage with his finger to withdraw the feeding member 240 when loading the magazine with a staple strip, this outer portion 262 also carrying another hook 266 positioned inwardly of the hook 264 which may be used if the outer hook happens to be located in an inconvenient position.

The shaft 256 supporting the coiled spring 252 is rotatably mounted in a housing or casing provided by a pair of vertical side plates 270, 272 (Figs. 1, 5 and 6) secured by screws 274 to the inner end of the bar 232 of the magazine, this casing also enclosing the spring and the staple inserting mechanism of the machine. As shown in Fig. 6, the shaft 256 has a slotted head 274 by which it may be turned in the casing to adjust the tension of the coiled spring and it has flattened side portions just rearwardly of the head whereby it may be held in adjusted position by a retaining plate 276 (Figs. 1 and 6) having a slotted upper end for engaging the flattened sides of the shaft, the retaining plate being fastened to the side plate 270 by a screw 278.

The inner edge of the rear plate 272, as viewed in Figs. 5 and 6, has a forwardly projecting wall 280 thereon which closes this end of the casing and, to the right of this wall, the plate has a relatively thick portion provided with a circular depression 282 for confining the coiled spring, the thinner front plate 270 fitting against this thick portion and the bar member 232 to close the forward side of the casing, as shown in Figs. 1, 5 and 6.

Pivoted on a horizontal pin 284 mounted in the side plates 270, 272 is a downwardly extending link 286 the lower end of which is pivotally connected by a pin 288 between ears on the outer end of a substantially horizontal link 290. The inner end of the link 290 is bifurcated to form ears and has pivotally connected between said ears by a pin 292 a driver bar 294 which is substantially rectangular in cross-section and projects upwardly into a slot or guideway 296 extending heightwise of the inner portion of the rear plate 272, the driver bar having a sliding fit in the guideway and the guideway being enlarged in width inwardly of the driver bar, as shown at 298 in Fig. 6. Rigidly secured by rivets to the inner surface of the driver bar 294 is a driver 300 which has a sliding fit widthwise in the enlarged portion 298 of the guideway and

is only slightly greater in thickness than the staples to be driven, the upper end of the driver 300 extending a substantial distance above the driver bar 294, as shown in Fig. 5, and its lower end being located in a slot 298 formed in the enlarged lower portion of the driver bar.

The enlarged inner portion 298 of the slot or guideway 296 is closed to provide a closed passageway 301 for the driver and staples by an elongated throat piece 302 which fits into the enlarged slot and is secured in place by pins or screws 304. The upper portion of the throat piece is cut away opposite the driver 300 to provide clearance for the staples by a vertical slot 306. Secured in the slot 306 by a rivet 308 is a leaf spring 310 which projects upwardly and outwardly and bears against the upper end of the back or outer wall of the passageway 301. The leaf spring 310 acts to prevent the bar portions of the staples, which are unsupported at their inner sides because of the clearance slot 306, from bending or buckling inwardly toward the throat piece under the force of the driver when the legs of the staples meet the resistance of the work piece or of the clinching anvil. The spring 310 bears against the bar portion of the staple as it is entering the work piece and helps to maintain the staple flat in the passageway until it has been fully inserted into the work, the spring, of course, being deflected by the staple and driver 300 as they pass the spring, as illustrated in Fig. 11. As shown in Fig. 5, the upper end of the throat piece 302 and the adjacent portions of the side plate 272 which enclose the throat piece are beveled downwardly at a substantial angle, as indicated by the numeral 312, to provide clearance and to adapt the stapling mechanism for properly engaging the work piece or shoe.

Returning now to the yielding pivotal connection 314 referred to above for supporting the outer end of the staple magazine 230, the bar member 232 of the magazine, as illustrated in Fig. 1, is pivotally connected near its outer end by the pin 314 between a pair of ears formed on the lower end of a cylindrical sleeve member 316, shown in section at the left-hand side of Fig. 1, the sleeve member 316 being rotatably mounted in a hole formed in a rectangular housing 318 projecting forwardly from the outer end of the supporting plate 130, the housing being preferably integral with the plate 130 and being inclined at an inward angle so that the sleeve member 316 will be substantially perpendicular to the magazine when the latter is in its operative position. The sleeve member 316 is also slidable heightwise of the housing 318 and the opening or hole therein is reduced in size at its lower end and is threaded to receive a threaded rod 320 which extends upwardly through the sleeve and is surrounded by a spring 322. The upper end of the spring 322 engages an adjustable collar 324 threaded into the upper end of the hole in the housing 318 and provided with a hexagonal head for turning it in the housing. The rod 320 extends upwardly through the collar 324 and has a pair of lock nuts 326 threaded on its upper end which engage the collar 324 and retain the rod and sleeve 316 in the housing 318, the tension of the spring 322 being determined or varied by the adjustable collar 324. This construction provides a pivotal or universal connection for the outer end of the staple magazine 230 which permits the latter to swing or rotate heightwise of the shoe support 58 about

the pivot 314, and also to swing laterally or widthwise of the support about the axis of the sleeve 316, the connection being yieldable heightwise, if necessary, by reason of the spring 322, although normally maintaining the magazine in its lowermost position, as shown in Fig. 1.

The intermediate portion of the magazine 230, as viewed in Figs. 1 and 5, is supported by a roll 328 rotatably mounted on the rearward side of the bar member 232 on a pin 330 and extending into a cam slot 332 formed in the curved upper portion of an arm 334 of a large, three-armed rotatable lever 336 fulcrumed on a fixed stud 338 (Figs. 1 and 3) secured to the plate 130 by a nut 340 on its rearward end, the lever 336 having an inwardly extending arm 342 and an outer arm 344, as best shown in Fig. 1. The fixed stud 338 extends some distance forwardly of the rotatable lever 336 and has pivotally mounted thereon an arm or lever 346 which extends inwardly toward the shoe support and has a rounded inner end 348 located directly below the driver bar 294 and in position to engage this bar and the connecting link 290 to operate the driver 300. This actuating or driving lever 346 has an outwardly projecting arm 350 which is much shorter than the lever itself and is normally engaged by a stop screw 352 threaded through a projection or lug 354 secured to the forward surface of the rotatable lever 336, this short arm 350 determining the inner or inoperative position of the rotatable lever when the mechanism is in its idle position, as shown in Fig. 1.

Mounted on the stud 338, in front of the driving lever 346, is a relatively heavy torsion spring 356 retained thereon by a washer 358 and a screw 360 and having its rearward end portion extending outwardly relatively to the support 58 and engaging a screw 362 threaded into the lever 336. The forward end 364 of the torsion spring 356 extends inwardly and engages a screw 366 secured in the driving lever 346 so that, when under tension, the spring 356 tends to swing the driving lever upwardly about the pivot 338 and to rotate the lever 336 inwardly about its fulcrum toward the center of the machine or in a counterclockwise direction, as viewed in Fig. 1, with respect to the right-hand mechanism of the machine. Consequently, the spring 356 tends normally to maintain the rotatable lever 336 in a position in which the roll 328 on the magazine 230 is located at the outer end of the cam slot 332, and it simultaneously urges the driving lever 346 upwardly in a direction to operate the driver bar, the driving lever, however, being normally retained in its lower or inoperative position by a latch 368 (Fig. 1) pivotally mounted on the plate 130 by a pin 370 and having a downwardly inclined arm which is notched to engage a small rectangular block 372 rigidly secured to the rearward side of the driving lever 346.

As shown in Fig. 1, the latch 368 of the right-hand mechanism of the machine is urged in a clockwise direction about the pivot 370 by a tension spring 374 secured to a pin on the latch and to another pin on the plate 130, the latch also having a short arm 376 extending from its upper end outwardly or toward the right. When the mechanism of the machine is at rest, as illustrated in Fig. 1, the latch 368 is in engagement with the fixed block 372 on the driving lever 346 and holds this lever against upward swinging movement under the action of the torsion spring 356. Since the driving lever is latched in a stationary position at this time, its outer arm 350

serves as a stop or abutment against which the screw 352 will be held through the force of the spring 356 acting upon the rotatable lever 336, this position being such, as stated, that the roll 328 on the magazine 230 will be located at the outer end of the cam slot 332 in said lever.

The outer arm 344 of the lever 336 has a rod 380 pivotally connected to it by a screw 378, the rod extending downwardly and being loosely connected by a pivoted or rotary block member 382 to a forwardly extending arm or lever 384 (Figs. 1, 2 and 3). The lever 384 is fulcrumed at its rearward end on a long horizontal shaft 386 extending widthwise of the machine and rotatably supported in a pair of arms 388, 390 which extend downwardly from a horizontal bracket 392 (Fig. 2) secured by bolts 394 to the lower surface of the plate or table 24 at the rear portion thereof, the shaft 386 being held against axial movement in the arms 388, 390 by collars 396, 398 secured to the shaft by set screws at opposite sides of the arm 388.

The lever 384 is fastened to the shaft 386 by a tapered pin 400 and has rigidly secured to its upper side by screws 402 a long, forwardly extending arm 404 (Figs. 1 and 3) provided at its front end with a handle 406 which may be grasped by the operator, the construction at the opposite side of the machine being substantially the same, as shown in Fig. 1, so that two handles 406 are provided at opposite ends of the long horizontal shaft 386, for swinging the levers 384 about the axis of the shaft, thereby preventing undue torsional strain on the shaft such as might result if only one handle were provided for operating the levers 384 pinned to the opposite ends of the shaft.

As indicated above, the type of shoe upon which the present machine is particularly adapted to operate is a stitchdown shoe, such as that illustrated in Figs. 8 to 13, inclusive, the illustrated shoe comprising at this stage of its construction an upper A, usually composed of a leather outer layer and a fabric inner layer or lining, the upper being mounted on a last C together with a leather sole member B which is temporarily secured to the last bottom in the usual manner by tacks or other fastening means. The sole member B may constitute the insole of the finished shoe, or, in a three-sole stitchdown construction, the mid-sole of the shoe. The marginal portion of the upper A is bent outwardly to provide an out-turned margin or flange F, as shown in Figs. 10 and 11, and the marginal portion of the sole member B projects outwardly beyond the periphery of the last bottom to provide the usual sole extension or "extension edge" E of the sole portion of the stitchdown shoe. The staples which are separated from the staple strips 233 in the stapling mechanisms of the machine and are inserted in the shoe at opposite sides of the last are indicated in Figs. 11 to 13 by the letter S. As shown in these figures, the staples S are inserted at predetermined distances away from the angle or crease formed by the side of the last and the out-turned margin F of the upper A and the staples are preferably located opposite or just rearwardly of the tip line of the upper. The upwardly projecting legs of the staples are clinched inwardly toward each other against the upper or exposed surface of the outer layer of the upper by the anvils 214, and the staples are positioned by the fastening-inserting mechanisms so that their bar portions and the clinched legs will lie substantially parallel to the periphery of the last bot-

tom or, in other words, to the edge face of the sole member B.

The handles 406 on the arms 388 for operating the levers 384 on the shaft 386 are depressed by the operator to cause the staples to be inserted and clinched in each side of the stitchdown shoe and thus to complete the operation of the machine on the shoe. These handles are not depressed, however, until after the gripping mechanisms have been operated by the treadle 166 and automatically locked in operated position, and also until after the shoe support 58 has been actuated by the treadle 44 to effect the relative movement which accomplishes the pulling-over operation, as described above, the treadle 44 being likewise latched automatically in operated position. When the gripping and pulling-over operations have been performed, however, the arms or levers 384 are depressed to lower the levers 384 at opposite sides of the machine and to pull down on the outer arms 344 of the rotatable levers 336 to swing the latter levers downwardly about their fulcrums 388 and to rotate the upper arms 334 outwardly, thereby moving the cam slots 332 outwardly. As shown, the cam slot 332 in each of the arms 334 is shaped so that its outer portion curves upwardly away from the fulcrum 388 and its inner portion is concentric with said fulcrum. Accordingly, during the first 20 part of the outward swinging movement of the lever 336, the roll 328 is moved upwardly by the cam slot and, during the remainder of the swinging movement, the roll is maintained in its elevated position due to the concentric portion 35 of the cam slot. Upward movement of the roll 328 swings the staple magazine 230 upwardly about the yieldable pivot 314 and moves the fastening inserting mechanism carried by said magazine into operative position relatively to the shoe, as 40 indicated in broken lines in Fig. 10, with the throat piece 302 pressing against the under side of the projecting sole member B. Since the out-turned margin F of the upper is at this time engaged by the grippers and also by the anvil 214, it will be clear that, when the throat piece presses upwardly against the sole member, these outwardly extending portions of the upper and sole member become clamped firmly between the fastening inserting mechanism and the stationary 50 anvil 214. The staple magazine remains in its elevated position during the rest of the swinging movement of the lever 336, during which time the fastening or staple S is driven and clinched against the upper.

Before the staple is driven, however, it is desirable to release the grippers 122, 144 at opposite sides of the shoe from gripping relation with the out-turned margin F of the upper A because the upper margin and projecting portion E of the sole member are now clamped firmly between the anvil 214 and the throat member 302, as shown in Figs. 10 and 11. Release of the grippers takes place automatically shortly after the staple inserting mechanism has been swung upwardly to engage and clamp the projecting sole member and upper margin between the throat piece and the anvil, the lower gripper 144 being indicated by broken lines in Fig. 10 in the position it assumes after it has been released.

It will also be seen from an inspection of Figs. 9 and 10, that a substantial portion of the out-turned margin F of the upper has been permitted to slip through the closed grippers 122, 144, this slipping action taking place during the pulling-

over operation on the shoe or, in other words, while the shoe support 58 was being moved upwardly and forwardly, as described above. This upward and forward movement of the shoe support is shown diagrammatically in Fig. 9 by indicating the initial or lower position of the support and shoe in broken lines and by illustrating in full lines a higher position where the support and shoe are being moved upwardly, this latter position being at a point in the pulling-over operation substantially at the beginning of the pulling or tensioning of the upper over the last C. Fig. 10 shows the gripping mechanism after the pulling-over operation has been completed or at a point in the cycle of operations of the machine where the shoe support has moved heightwise its full distance so that the projecting margin E of the sole member B is located about opposite the tooth 146 on the lower gripper 144. It can be seen from these two figures that the outturned margin F of the upper has slipped or pulled through the grippers an appreciable amount under the tension of the pulling-over operation. The interlocking or toothed construction of the grippers 122, 144 is provided for the purpose of permitting this slipping action, this mechanism operating to grip and hold the upper margin with sufficient tension to produce a good pulling-over operation while, at the same time, permitting the upper to slip or pull through the grippers when the pull or tension on the upper exceeds a predetermined amount, as it usually does before the operation is completed.

The automatic release of the grippers 122, 144 is accomplished at the proper time in the operation of the machine by throwing out the latch 198 at the left-hand side of the machine which holds the rod 190 in its lowermost position and thereby locks the toggles 152, 156 in their straightened or operated positions. As pointed out above, the latch 198 is clamped to the pin 196 rotatably mounted in the plate 130, this pin having the member 206 secured to its rearward end. The member 206 is urged in a clockwise direction by the spring 210 to hold its inner arm 207 against the stop pin 209 and it has a pair of ears on its outer end between which is pivotally connected, by a pin 405, a downwardly extending link 407 having an elongated slot 409 in its lower portion in which is located a rearwardly projecting portion 411 of the pin or screw 378, this rearward portion 411 being supported by a rigid arm 413 secured by screws to the rear side of the rotatable lever 336. When the lever 336 is swung downwardly by depression of the levers 404, the pin 411 moves down in the slot 409 and engages the bottom of the slot to lower the link 407 which, through the mechanism described above, swings the latch 198 inwardly or counterclockwise and releases the rod 190 for upward movement into its initial position. Since the rod 190 engages the block on the arm 186 which, in turn, is pinned to the rotatable shaft 46, it will be clear that release of the rod 190 also releases the shaft 46 for rotation which is then effected by the spring 180 to elevate the treadle 166 against the stop screw 182 and to raise the rod 190 and opposite rod 164, thereby breaking both gripper toggles 152, 156 simultaneously and causing the lower grippers 144 to swing downwardly into the open position shown in Fig. 1, and indicated in broken lines in Fig. 10. The latch 198 will be maintained bearing against the pin 162 by the spring 210 after release of the latch so that the

latter will be in position to snap over the pin 162 and latch the rod 190 down again the next time it is depressed.

As the lever 336 of each unit is swung downwardly by the hand levers 404, the torsion spring 356 is wound tighter, thereby putting greater tension on the driving lever 346. At the same time, the inner arm 342 of the lever 336 is swung upwardly and, at the proper moment, engages the projection 376 on the latch 368 and swings the latch outwardly away from the block 372 on the driving lever, thereby permitting this lever to snap upwardly under the force of the torsion spring to strike the link 290 and driver bar 294 and operate the driver 300. The driver moves upwardly in its passageway to separate the innermost staple S from the staple strip 238 and to drive the staple upwardly with considerable force through the guideway and into the work piece, 20 the staple, as illustrated in Figs. 11 and 12, entering the bottom surface of the projecting sole member B and passing upwardly through it and the outturned margin of the upper, and being clinched against the upper or exposed surface of 25 said margin by the anvil 214.

The stapling mechanisms, including the magazines 230 and the staple inserting means, are returned to inoperative position automatically by a tension spring 420 (Fig. 2) attached at its 30 forward end to a pin in the frame 20 and, at its rearward end, to another pin in the lower end of an arm 422 fastened by a tapered pin 424 to the shaft 386 to which the hand levers 404 are attached. When the hand levers are released by 35 the operator and permitted to rise, after the fastenings have been inserted, the spring 420 pulls the arm 422 forwardly to rotate the shaft 386 in a clockwise direction, as viewed in Fig. 2, and thereby to elevate the arms 384 and rods 380 to move the staple magazines and inserting mechanisms into the inoperative positions they occupy in Fig. 1 by the inward movement of the rotatable levers 336.

45 It will be noted, however, that while the levers 346 which activate the driver bars and drivers are returned positively to inoperative position by the stop screws 252 on the outer arms 334 of the levers 336, and also while they become latched down again automatically by the latches 368, the drivers and driver bars themselves are separate from these actuating mechanisms and therefore are not retracted by the positive return of the levers 336 to inoperative position. The driver bar 294 and driver 300 of each stapling mechanism are 50 returned to inoperative position by a compression spring 426 (Figs. 5 and 6) mounted in a hole formed in a long, square block or bar 428 rigidly secured in an upright position to the rearward side of the casing plate 272 adjacent to the inner end of the staple magazine. As best shown in Fig. 5, the upper end of the spring 426 engages the closed end of the hole and its lower end bears against a cylindrical plunger 430 slidably mounted in the hole and engaging a pin 432 projecting rearwardly from the link 290, the pin extending into a slot 434 formed near the lower end of the bar member 428 so that the pin can move heightwise relatively to the bar 428. When 55 the driving lever 346 is retracted the spring 426 automatically returns the driver bar and driver to their inoperative position which is determined by the pin 432 engaging the lower end of the slot 434 in the bar 428, as shown in Fig. 5.

70 As stated above, the illustrated machine is pro-

vided with mechanism for initially adjusting the supporting plates 130 to vary the positions of the operating mechanisms carried thereby, including the grippers, fastening inserting means and anvils, relatively to the shoe support 58 in order to adapt these mechanisms for operating upon shoes of different shapes, styles or sizes, or, in other words, to locate these mechanisms at the proper positions and angles for operating on the opposite sides of the foreparts of the different shoes. In addition to the adjusting mechanism referred to, the machine is also provided with further mechanism for moving the supporting plates 130 inwardly toward the shoe shortly before the insertion of the staples to cause the anvils 214 and stapling mechanisms to move inwardly relatively to the shoe with a yielding action to press the upper firmly into the angle or crease between the last and the projecting margin of the sole and thereby to cause the upper to be positioned as tightly as possible around the forepart of the last and also to locate the staples in the desired widthwise position with respect to the upper while so held, this inward movement of the mechanism taking place after the throat piece 302 has been swung upwardly into engagement with the sole member to grip it and the upper firmly between said throat piece and the anvil, as illustrated in Fig. 11.

Referring to Figs. 2 and 3, the table 24 has rigidly secured to its rear portion by screws 436 a bracket 438 comprising a wide vertical plate 440 extending transversely of the table and supported by two rear plates or ribs 442 to which the plate 440 is attached by screws 444 (Fig. 2). On the forward surface of the plate 440 are provided a pair of vertical projections or lugs 446 of substantial length to which are pivotally secured by pins 448 a pair of swinging carrier members 450 consisting of thick, vertical plates each of which has rearwardly projecting ears 452 located respectively at its upper and lower ends through which the pin 448 passes.

At the front end of each swinging member 450 is provided another pair of ears 454 which project forwardly and between which is pivotally mounted by a pin 456 the plate 130 which carries the grippers, anvil and fastening inserting mechanism of the machine. It will be seen from the foregoing that each supporting plate 130 is movable widthwise or laterally of the machine toward or away from the shoe support 58 by reason of the pivoted carrier member 450, and that each plate 130 is also rotatable relatively to the shoe support about the pivot 456 which connects the plate to the carrier member. This construction permits the plate 130 to be rotated into different angular positions with respect to the shoe support to locate the mechanism carried by the plate at the proper angle for operating upon the shoe on the support.

Secured by screws to the outer portion of each supporting plate 130 is an L-shaped bracket 458 which projects rearwardly and has pivotally connected thereto by a pin 460 a link 462 which extends rearwardly over a cut-out portion in the bracket 440 and is pivotally connected at its other end by a removable pin 464 to another L-shaped bracket 466 fastened to the plate 440, the connection at the rear end of the link being adjustable by reason of a series of holes 468 (Fig. 3) formed in the link into one of which the pin 464 may be inserted to connect the link in the desired position to the fixed bracket 466.

Secured to the outer side of each of the car-

rier members 450 is an elongated vertical plate or bar 470 the lower end of which is turned outwardly and has pivotally connected to it by a screw 472 a rod or eye-bolt 474 which extends outwardly substantially at right angles to the member 450 and, at its outer portion, passes slidably through a block 476 (Figs. 3 and 4) rotatably mounted on the rearward end of a long horizontal lever 478 by a pin or shank 480 integral with the block, the horizontal lever 478 extending forwardly of the machine in substantially the same plane as the table 24, as shown in Figs. 1 and 3. A collar 482 is fastened by a set screw to the inner portion of the eye-bolt 474 and surrounding the bolt, between the collar and the rotary block 476, is a compression spring 484, the tension of which may be determined or adjusted by a pair of lock nuts 486 threaded on the rod.

20 The horizontal levers 478 at the opposite sides of the machine, which carry the rotary blocks 476, are normally parallel to each other and are pivoted about midway of their lengths on vertical pins 488 secured by set screws to a pair of swinging levers or arms 490, 492 located respectively below the left- and right-hand levers 478, as viewed in Fig. 3, the arms 490, 492 being arranged for swinging movement relatively to the levers 478, as will be hereinafter explained. The horizontal levers 478 extend forwardly of their pivots 488 and, at their forward ends adjacent to the front of the machine, are provided respectively with rotatable blocks 494 mounted on the lower sides of the levers by means of integral pins or shanks 496 which are threaded at their upper ends to receive nuts 498 for securing the blocks to the levers.

Extending transversely across the front of the machine is a long horizontal shaft 500 rotatably mounted in a supporting block or bearing 502 attached by a stem or shank 504 to the lower side of the table 24, the shaft 500 being prevented from endwise movement in the block 502 by a pair of collars 506 secured to the shaft at opposite sides of the block by set screws. At its opposite end portions the shaft 500 is provided, respectively, with right- and left-hand threaded sections 508, 510 which are threaded through holes in the rotary blocks 494 on the levers 478. At its right-hand end, as viewed in Figs. 1 and 3, the shaft 500 is provided with a hand wheel 512 by which it may be rotated manually in the block 502 so that rotation of the shaft produces equal and opposite movement of the front ends of the levers 478 toward or away from each other. The shaft 500, therefore, provides manually operated means whereby the normally parallel horizontal levers 478 may be adjusted about their pivots 488 to swing their rearward ends equally and oppositely toward or away from each other. Such adjustment, through the yieldable connections provided by the rods 474 and springs 484 between the levers 478 and the pivoted carrier members 450, causes the carrier members to swing about their pivots 448 in the lugs 446 the same amount and in the same direction as the rearward ends of the corresponding levers 478, no appreciable yield taking place in the connections at this time because there is nothing to obstruct the swinging movement of the members 450 or to cause compression of the springs 484.

Since the pivoted members 450 carry the supporting plates 130 at their forward ends, to which the latter are pivotally connected by the pins 456, it will be clear that the plates 130 and the

operating instrumentalities carried thereby may be adjusted simultaneously equal amounts toward or away from the support 58 or a shoe mounted thereon in order to locate the operating mechanisms of the machine, that is, the grippers, anvils and fastening inserting mechanisms in the desired positions widthwise of the shoe. Moreover, as pointed out above, the angular positions of the supporting plates 130 relatively to a shoe on the support 58 may likewise be initially adjusted by reason of the manual adjustments provided by the removable pins 464 and the series of holes 468 in the links 462, the plates 130 swinging about the forward pins 456 during the angular adjustment. After a shoe has been mounted and positioned upon the support 58, the operator adapts the opposite mechanisms for operating on that particular shoe by making the adjustments described above, the angular adjustment usually being made first and the widthwise adjustment last in order to position the mechanisms accurately for operating upon the shoe. If the shoes to be operated upon are of the same general shape or style and do not vary greatly in size, the initial adjustments of the operating mechanisms angularly and widthwise will in most cases be sufficient for operating upon an entire lot of shoes.

The swinging arm 490 above referred to, which carries the pivot pin 488 for the left-hand horizontal lever 478, is fulcrumed on a vertical stud 514 (Figs. 3 and 4) secured by a nut 516 to a stationary bar 518 extending widthwise of the machine below the arm 490 and rigidly secured to the table 24 by bolts 520. The opposite arm 492 is pivoted on a fixed stud 522 fastened by a nut to the crossbar 518. As illustrated in Fig. 3, the swinging arm 492 extends forwardly of its pivot 522 whereas the opposite arm 490 extends rearwardly from its pivot 514. The arm 490 has a slot or opening 524 (Fig. 4) formed therein in which is pivotally secured by a pin 526 a horizontal link 528 which extends diagonally across the machine and is pivotally connected at its other end by a pin 530 to the bifurcated forward end of the opposite swinging arm 492. Rotary or swinging movement of the left-hand arm 490 about its pivot 514, therefore, will, through the link 528, impart to the right-hand arm 492 equal rotary movement about its pivot 522 but in an opposite direction.

The transverse shaft 386 at the rear of the machine, upon which the two arms 384 and hand levers 404 are mounted, and which is rotated by said hand levers to actuate the fastening inserting mechanisms of the machine, has rigidly secured to its right-hand portion by a taper pin 532 (Figs. 1 and 3) an upwardly extending arm 534 to the upper end of which is pivotally connected in any usual manner a forwardly extending rod or link 536. The front end of the rod 536 is threaded into a connecting member 538 having ears which straddle the right-hand end of a relatively wide, horizontal lever 540, the rod being pivotally connected to the lever by a pin 542 passing through said ears. The lever 540, as illustrated in Figs. 1, 2 and 3, extends transversely across the machine and is fulcrumed a little to the right of its central portion on a short vertical shaft 544 secured by a set screw 546 in a rectangular casting or block 548 fastened to the under side of the table 24 by bolts 550, the shaft 544 extending upwardly through the table 24, as shown in Fig. 2. The rectangular block 548 is

slotted horizontally at 552 to support the central portion of the horizontal lever 540 which, as shown in Figs. 3 and 4, extends toward the left and terminates below the swinging arm 490 in an enlarged, oval-shaped portion 554. The enlarged portion 554 of the lever has a cam slot 556 formed therein which, as illustrated, is substantially concentric with the fulcrum 544 of the lever 540 at its opposite portions but curves sharply inwardly or toward the center of the machine at its intermediate portion. Positioned in this cam slot is a roll 558 rotatable upon a downwardly projecting pin 560 secured by a set screw in the rear end of the swinging arm 490, as shown in Figs. 3 and 4.

In operation, the mechanism described above acts at the proper time in the sequence of operations of the machine to move the anvils 214 and the other operating mechanisms at opposite sides 20 of the machine inwardly toward the shoe from their open or starting position, indicated by the broken line X in Fig. 9, into their operated or final position, illustrated by the broken line Y in Fig. 10. When the operator depresses the hand levers 404 to cause the staple magazines and fastening inserting mechanisms to swing upwardly to grip the shoe upper between the anvils and throat pieces and also to release the grippers, as described above, the arm 534 on the rear shaft 386 swings forwardly to rotate the cam lever 540 about its pivot 544 in a clockwise direction, as viewed in Fig. 3, thereby swinging the opposite end of this lever and the cam slot 556 rearwardly so that the roll 558 on the arm 490 is swung sharply inwardly or toward the right about its pivot 514 by the shape of the cam slot 556. Inward movement of the swinging arm 554 causes a reverse or outward swinging movement of the opposite arm 492 about its pivot 40 522 through the connecting link 528.

As explained above, the swinging arms 490, 492 carry the fixed pivots 488 about which the horizontal levers 478 fulcrum when they are adjusted manually by rotation of the oppositely 45 threaded screw 508 to move the supporting plates 130 and the operating mechanisms toward or away from the shoe support 58 in order to position these mechanisms initially for operating upon the shoe. It will be noted, moreover, that the two pivots 488 for the levers 478 (Fig. 3) are located rearwardly of the fulcrums 514, 522 for the swinging arms 490, 492 so that inward swinging movement of the left-hand arm 490, and reverse or outward movement of the right-hand arm 492, moves both pivots 488 inwardly toward the center of the machine and toward the shoe support 58. This inward movement of the pivots 488 for the levers 478 causes these levers to swing inwardly about fulcrums now 50 provided by their pivotal connections to the oppositely threaded rod or screw 508 or, in other words, about the centers of the shanks 496 of the rotatable blocks 494. The rearward ends of the levers 478, therefore, are automatically swung 55 inwardly by this action and, through their yielding connections to the carrier members 450 provided by the eye-bolts 474 and springs 484, cause these latter members to swing inwardly about their pivots 448 and thereby to move the opposite plates 130 inwardly toward the shoe, this action, of course, being yieldable because the inward movement of the levers 478 is transmitted or applied through the springs 484 surrounding the eye-bolts 474. After the operating mechanisms at each side of the machine have been

thus moved inwardly a predetermined distance to press the upper margin F tightly into the angle formed by the projecting sole member and the side of the last, the anvil and throat piece are caused to remain in such position, as illustrated in Figs. 10 and 11, while the staple is driven because of the concentric forward portion of the cam slot 556 in the horizontal lever 549.

Although the operation of the machine will be apparent from the foregoing description, a brief summary will be given here for the purpose of clearness. The operator mounts a stitchdown shoe on the support 58, the shoe preferably comprising the usual two-ply upper, such as the upper A, illustrated in Figs. 8 to 13, inclusive, the upper being assembled loosely on the last C with a sole member B which is temporarily secured to the last bottom by tacks or similar means. As shown in the figures referred to, the sole member B, which may constitute either the insole or the midsole of the finished shoe depending upon the type of stitchdown shoe to be made, projects beyond the edge of the last bottom in the usual manner to provide the sole extension or margin E to which the outturned margin F of the upper is to be attached when the upper is lasted.

The operator adjusts the toe gage 74 and the side gages 181 as much as may be necessary for the size and shape of the shoe being operated upon, the toe gage 74 being adjusted, as explained above, by loosening the clamping screws 73 and threading the adjusting screw 80 into or out of the block 76. The side gages 181 may be adjusted or set widthwise by moving them in the slots 185 and then tightening the screws 183.

After positioning the gages properly for the shoe, the operator will adjust the opposite operating mechanisms of the machine into the proper widthwise positions relatively to the support 58, and he will also adjust them into the proper angular positions relatively to the opposite sides or edges of the forepart of the last in the shoe. It should be pointed out that the shoe support 58, as shown in Figs. 1, 2 and 11, is cut away at the portion opposite the operating mechanisms of the machine to permit these mechanisms to move inwardly far enough to come into operative engagement with the shoe.

In adjusting the operating mechanisms widthwise, as pointed out above, the operator turns the hand wheel 512 to rotate the screw 538 and thereby to swing the carrier members 450 and supporting plates 130 toward or away from the shoe support through the movement of the horizontal levers 478 and the pivotal connections between them and the carrier members 450. In order to shift the operating mechanisms angularly with respect to the shoe, the operator merely removes the rear pins 464 from the links 462 and swings the supporting plates 130 into the angular positions which, in his judgment, are best suited for the shoe being operated upon, and then inserts each pin 464 in the proper hole 468 in the link to maintain the supporting plates in such angular positions.

After having made the necessary adjustments for the shoe being operated upon and thereby positioned the mechanisms properly not only for that shoe, but for an entire lot or run of shoes of substantially the same size and shape, the operator makes sure that the opposite marginal portions of the forepart of the shoe upper overlie the grippers and are in position to be gripped thereby when the grippers are operated. The

operator then depresses the treadle 166 (Fig. 1) to straighten the toggles 152, 156 of the opposite gripping mechanisms which causes the lower gripper jaw 144 to swing upwardly and to grip the margin of the upper between it and the upper gripper 122, as illustrated in Fig. 9. The gripping mechanisms become locked automatically in operated positions by the latch 198 at the left-hand side of the machine, so that the operator may remove his foot from the treadle immediately and proceed with operating the rest of the mechanisms.

He next depresses the treadle 44 to cause the shoe support 58 to move upwardly and forwardly to perform the pulling-over operation on the shoe, this movement of the support being caused, as explained above, by elevation of the parallel arms 50, 52 (Fig. 2) through the straightening of the toggle 34, 36 while, at the same time, the parallel links 94 on the toggle are moved forwardly by movement of the rear link 36 to cause the arm 50 to swing forwardly and to move the shoe support in a forward direction, the support remaining horizontal throughout this movement because of the parallel arms. The operator usually holds the shoe steady on the support during this operation by placing his hand on the cone of the last and pressing the last lightly against the support to prevent accidental movement or displacement of the shoe. Fig. 9 illustrates somewhat diagrammatically the heightwise movement of the shoe support from its initial position to a point where the grippers are just beginning to put tension or pull on the upper although not, as yet, sufficient tension to cause the upper to slip through the grippers as it will later in the pulling-over operation after the tension on the upper becomes greater. When the support 58 has completed its upward and forward movement, it becomes latched automatically in its operated position by the latches 104, 106 which drop under the pin 49 at the forward end of the toggle 34, 36 and thus hold the toggle in its straightened position.

If the upper has not been pulled over properly or has become twisted or displaced during this part of the pulling-over operation, the operator may, if he so desires, stop the operation before it has been completed and inspect the shoe without entirely releasing the mechanisms, this being possible, as explained above, because the latch 106 for locking the toggle 34, 36 is notched slightly lower than the opposite latch 104, which permits the operator to stop the machine while the mechanisms are held by the lower latch 106 in the positions they then occupy. If he should find that the shoe or upper has become displaced or was being pulled over unevenly, he can release the shoe support 58 by means of the handles 118, 120 on the latches 104, 106 and thus permit the toggle to break and the support to return to its initial or lower position. Furthermore, if it should become necessary to release the grippers in order to reposition the shoe or to straighten the upper before proceeding, the operator can also release the gripping mechanisms by means of the upstanding projection or handle 212 (Fig. 1) which disconnects the latch 198 and permits the gripper toggles to break and thereby permits the grippers to open and return to their inoperative positions. If an inspection indicates that the shoe is being held and pulled over properly, the operator resumes the depression of the treadle 75 44 toward its final or lowermost position at

which point the higher latch 104 (Fig. 2) drops under the pin 49 and locks the shoe support in its elevated position.

The shoe has now been pulled over the last and the forepart, back part and side portions of the upper have been pulled firmly against the last by the forward and upward movement of the shoe support relatively to the stationary gripping mechanisms. Moreover, the opposite margins of the upper held by the grippers have been permitted to slip through the grippers as much as was necessary to prevent tearing the upper while, at the same time, being held firmly enough to produce a good pulling-over action so that the upper will lie smooth and flat against the forepart of the last. The operator now grasps the opposite handles 406 and depresses the hand levers 404 which cause the remaining operations of the machine to take place, these operations comprising first, the clamping of the upper margin F and the sole extension E between the throat pieces 302 and anvils 214, secondly, the automatic release of the opposite gripping mechanisms, thirdly, the inward movement of the operating mechanisms toward the support to insure that the upper is positioned or pressed tightly against the last at the angle or crease adjacent to the last bottom, and, finally, the inserting or driving of the staples and clinching of them against the upper surface of the outturned margin of the upper.

As explained above, as the hand levers 404 are moved downwardly, the rotatable levers 336 at opposite sides of the machine swing outwardly to elevate the rolls 328 in the cam slots 332 of the upper arms 334 of the rotatable levers. Upward movement of these rolls causes the staple magazines to swing upwardly about their yieldable pivots 314 toward the position shown in Fig. 11, where they will engage the sole extension E and grip it and the margin F between the throat pieces 302 and the anvils 214. Before this upward movement is completed, however, but after the throat pieces have moved into gripping relation with the sole and upper, the latch 198 (Fig. 1) for the grippers is automatically released by the pin 411 engaging the bottom of the slot 409 in the link 407 and pulling downwardly on the member 206 to swing the latch inwardly and release it from engagement with the pin 162.

After the upper margin and projecting sole member have been tightly clamped between the throat piece and the anvil 214, and after the grippers have been released, the mechanisms are retained in this clamping relation until after the staples have been driven, due to the shape of the inner portions of the cam slots 332, which are concentric with the axes of the studs 338 about which the levers 336 rotate. Accordingly, the upper and sole member will remain clamped until they are secured in this position by the fastening means or staples. As the hand levers 404 are depressed toward their lowermost positions, the rotation of the shaft 386 to which they are pinned swings the arm 534 forwardly and, through the connection 536, causes the horizontal cam lever 540 to be swung in a clockwise direction, as viewed in Fig. 3, about the pivot 544 to move the left-hand end of this lever and the cam slot 556 rearwardly, thereby swinging the arm 490 inwardly about the fixed pivot 514. This movement of the arm 490 swings the opposite arm 492 outwardly so that the central pivots 488 for the horizontal levers 478 are moved inwardly equal distances as

determined by the cam slot 556. The levers 478 are thus caused to swing about the forward pivots 496 on the adjusting screw 533 so that their inner ends swing inwardly predetermined amounts.

- 5 The yielding connections between the inner ends of the levers 478 and the carrier members 450, swing the carrier members inwardly about their vertical pivots 446 and move the opposite plates 130 inwardly toward the shoe support but with a 10 yielding action provided by the springs 484. The effect of this mechanism, therefore, is to move each throat piece 302 and each anvil 214, which are now in gripping relation with the sole member and upper, inwardly toward the support with 15 a yielding action to press the upper into closer engagement with the sides of the last, particularly the lower portion of the upper adjacent to the angle between the last and the sole margin or extension E. While this movement is usually 20 relatively slight, it may, in some cases, be sufficient to be noticeable. An illustration of this inward movement is indicated diagrammatically by the broken lines X and Y in Figs. 9 and 11, respectively, the line X showing the position of 25 the mechanism before the inward movement and the line Y showing its position after such movement.

When the inward movement of the throat piece and anvil has taken place, final depression of the hand levers 404 actuates the staple inserting mechanisms of the machine to complete the operation upon the shoe, the driving of the staples, as pointed out above, being accomplished by upward movement of the inner arms 342 of the rotatable levers 336 into engagement with the projections 376 on the latches 368 to release these latches from the lugs 372 on the driving levers 346 and to permit the latter to operate, the torsion springs 359 being wound tighter by the outward movement of the levers 336 so that tension or load on the driving levers is increased prior to the driving operation. Release of the latches 368 permits the driving levers to snap upwardly 40 to operate the drivers 390 and cause them to break off a staple S from the strips 298 and to insert it in the clamped portions of the sole member and upper, as shown in Figs. 11 and 12, the staple S being clinched against the upper or exposed surface of the upper margin F by the anvil 214.

Figs. 11 to 13, inclusive, show that the staple S is driven parallel to the edge face of the sole member B and is clinched by the anvil so that 55 the clinched portions of the legs are turned inwardly toward each other and lie parallel to the edge face of the sole. As illustrated in Fig. 13, the staples are located a relatively short distance outwardly from the crease or angle between the side of the upper and its outturned margin, this distance being important because it is desirable to have the staples located sufficiently close to this crease to constitute a satisfactory pulling-over operation while, on the other hand, they 60 should also be spaced outwardly from the side portion of the upper a sufficient distance to permit the permanent stitches inserted in the stitch-down lasting operation to pass between the side of the upper and the staples without running into or striking the staples and either breaking the needle of the stitching machine, or severing or 65 damaging the thread forming the stitches.

After the staples have been inserted and clinched in the shoe parts in the manner described, the operator releases the hand levers 404

and permits them to return to their initial elevated positions by the spring 420 (Fig. 2) which, in turn, causes the levers 336 to swing inwardly to return the staple magazines and associated mechanisms to their original or inoperative positions. Since the driver bars and drivers are separate from the driving levers 346, the drivers 390 do not return to inoperative position by reason of the return of the driving levers into their latched positions, as illustrated in Fig. 1, and, consequently, the compression springs 426 (Fig. 5) function at this time to retract the drivers and driver bars to their lowermost positions below the staple strips 238, thereby permitting the staple strip to be fed forwardly into the driver passage under the action of the feeding member and coiled spring 252 and thus locate another staple in position for the next shoe to be operated upon.

After the staple magazines and associated mechanisms, including the driving levers and drivers, have been returned automatically to their inoperative positions, the shoe support 58 may be released from its elevated and forward position and caused to return to its initial lower position, as shown in Fig. 2, by tripping the latches 104, 106 manually by their handles 118, 120, to permit the treadle rod 42 to be raised by the spring 48 to break the toggle 34, 36 and cause it to assume the position shown in Fig. 2, this position being determined by the forward stop screw 100 on the toggle link 34. The operator may then remove the pulled-over stitchdown shoe from the support 58, mount the next shoe thereon, and repeat the operations described above, the adjustments of the toe and side gages and the operating mechanisms, however, being necessary only when the next shoe to be operated upon differs substantially in size and shape from the last shoe operated upon.

While the invention has been disclosed herein with reference to machines adapted for use in performing pulling-over operations upon shoes, and more particularly, in performing such operations upon stitchdown shoes, it is obvious that, in its broader aspects, the invention is not limited to such operation or to operating only upon stitchdown shoes, since many of its features and advantages could be employed with equally beneficial results in connection with other operations upon shoes, such operations, for example, as the assembling or lasting operations, and the invention or features thereof could also be utilized to advantage in connection with the manufacture of shoes other than stitchdown shoes.

Having thus described our invention, what we claim as new and desire to secure by Letters Patent of the United States is:

1. A machine for use in the manufacture of shoes having, in combination, a support for a last having an upper and a projecting sole member mounted thereon, mechanism for gripping the margins of the upper at opposite sides of the last and holding them in an outturned position, means for effecting relative movement of the support and gripping mechanism heightwise of the last to pull the upper over the last, and means for inserting metallic fastenings through the projecting sole member and the outturned margins of the upper at opposite sides of the last to hold the upper in pulled-over position on the last.

2. A machine for use in the manufacture of shoes having, in combination, a support for a last having an upper and a sole member mounted thereon, said sole member projecting beyond the edge of the last bottom, mechanisms for gripping

the margins of the upper at opposite sides of the last and holding said margins in an outturned position over the projecting sole member, means for effecting relative movement of said support and said gripping mechanisms heightwise of the last to pull the upper over the last, and means for inserting a staple through the sole member and upper at each side of the last adjacent to the gripping mechanisms to secure the upper in pulled-over position, said inserting means being constructed and arranged to insert the staples first through the sole member and then through the upper.

3. A machine for use in the manufacture of shoes having, in combination, a support for a last having an upper and a sole member mounted thereon, upper gripping mechanisms at opposite sides of the support at the forepart of the last, means for causing relative movement of the support and gripping mechanisms heightwise of the last to pull the upper over the last, and fastening inserting means at opposite sides of the support for inserting staples simultaneously through the sole member and upper at opposite sides of the last to hold the upper in pulled-over relation thereto, said inserting means being constructed and arranged to drive the staples upwardly in an inverted position through the sole member and upper and to clinch the staples against the exposed surface of the upper.

4. A machine for use in the manufacture of stitchdown shoes having, in combination, a support for a last having assembled thereon a sole member which projects beyond the last bottom and an upper the margin of which is turned outwardly over the projecting sole member, gripping mechanisms at opposite sides of the support at the forepart of the last for gripping the outturned margins of the upper, means for effecting relative movement of the support and gripping mechanisms heightwise of the last to cause the upper to be pulled over the last with its outturned margins positioned flat against the projecting sole member, and fastening inserting means at opposite sides of the support adjacent to the gripping mechanisms for inserting metallic fastenings through the projecting sole member and the outturned margins of the upper at opposite sides of the last to hold the upper in pulled-over position relatively to the last and sole member.

5. A machine for use in the manufacture of shoes having, in combination, a support for a last having an upper and a sole member assembled thereon, mechanisms at opposite sides of the support at the forepart of the last for gripping the margins of the upper at opposite sides of the last, means for causing relative movement of the support and gripping mechanisms heightwise and lengthwise of the last to pull over the upper on the last, fastening inserting means at opposite sides of the support for inserting metallic fastenings through the upper and sole member at each side of the last to secure the upper in pulled-over position thereon, said inserting means being constructed and arranged to insert the fastening first through the sole member and then through the upper, and anvils for engaging the upper and clinching the fastenings against the exposed surface thereof.

6. A machine for use in the manufacture of stitchdown shoes having, in combination, a support for a last having an upper and a projecting sole member mounted thereon, grippers at opposite sides of the support for gripping the margins of the upper at opposite sides of the

last, means for effecting relative movement of the support and grippers heightwise of the last to pull the upper over the last with its opposite margins turned outwardly over the projecting sole member, and means for inserting staples simultaneously through the materials at opposite sides of the last adjacent to the grippers to hold the upper in pulled-over relation to the last, said inserting means being constructed and arranged to insert the staples parallel to the edge of the sole member and in an inverted position into the bottom of said sole member and then upwardly through the outturned margins of the upper and being also arranged to clinch the staples against the upper surfaces of said outturned margins.

7. A machine for use in the manufacture of stitchdown shoes having, in combination, a support for a last having an upper and a projecting sole member mounted thereon, grippers at opposite sides of the support at the forepart of the last for gripping the opposite margins of the upper and holding them in an outturned position, means for effecting relative movement of the support and grippers heightwise and lengthwise of the last to cause the upper to be pulled over the last with its opposite margins extending outwardly over the projecting sole member, means for clamping the outturned margins of the upper against the projecting sole member, and means for inserting metallic fastenings through the clamped sole member and upper margins and for clinching said fastenings against said margins.

8. A machine for use in the manufacture of shoes having, in combination, a support for a last having an upper and a sole member mounted thereon, the margin of said sole member projecting beyond the periphery of the last bottom, gripping mechanisms at opposite sides of the support at the forepart of the last for gripping the opposite margins of the upper and holding them in an outturned position above the projecting margin of the sole member, means for effecting relative movement of said support and gripping mechanisms heightwise of the last to pull the upper over the last with its opposite margins overlying the projecting margin of the sole member, means for clamping the outturned upper margins against the projecting margin of the sole member at opposite sides of the last, fastening inserting means at opposite sides of the support for inserting fastenings through the clamped margins of the sole member and upper adjacent to the gripping mechanisms to secure the upper in pulled-over position on the last, and means for actuating said fastening inserting means to drive the fastenings, said actuating means being constructed and arranged also to actuate said clamping means.

9. A machine for use in the manufacture of shoes having, in combination, a support for a last having an upper and a sole member mounted thereon, mechanisms at opposite sides of the support at the forepart of the last for gripping the opposite margins of the upper and holding them in position to engage the sole member, means for effecting relative movement of the support and gripping mechanisms to bring the upper margins into engagement with the sole member, fastening inserting means at opposite sides of the support adjacent to said gripping mechanisms, said inserting means being arranged for swinging movement heightwise of the support toward and away from the work thereon, and means for actuating said fastening inserting means to in-

sert fastenings through the sole member and upper at opposite sides of the last, said actuating means being also arranged to swing the fastening inserting means into engagement with the work prior to actuating said inserting means.

10. A machine for use in the manufacture of stitchdown shoes having, in combination, a support for a last having an upper and a sole member mounted thereon with the sole member projecting beyond the last bottom, grippers at opposite sides of the support at the forepart of the last for gripping the opposite margins of the upper and holding them in an outturned position over the projecting sole member, means for effecting relative movement of the support and grippers heightwise of the last to cause the upper to be pulled over the last with its opposite margins overlying the projecting sole member, fastening inserting means at opposite sides of the support for inserting fastenings through the opposite margins of the sole member and upper to secure the upper in pulled-over relation to the last, said fastening inserting means being arranged for swinging movement heightwise of the support toward and away from the shoe thereon, and treadle operated means for actuating said fastening inserting means to insert said fastenings, said treadle operated means being also arranged to swing said inserting means into engagement with the sole member before the fastenings are inserted.

11. A machine for use in the manufacture of shoes having, in combination, a support for a last having an upper and a sole member mounted thereon with the margin of the sole member projecting beyond the last bottom, grippers at opposite sides of the support at the forepart of the last for gripping the opposite margins of the upper and holding them in an outturned position, means for effecting relative movement of the support and grippers heightwise and lengthwise of the last to cause the upper to be pulled over the last with its margins overlying the projecting margin of the sole member, mechanisms at opposite sides of the support and arranged for movement relatively thereto for inserting fastenings through the sole member and upper to secure the upper in pulled-over position on the last, anvils cooperating with said fastening inserting mechanisms to clinch the fastenings after they have been inserted, and means for actuating the fastening inserting mechanisms constructed and arranged first to move said mechanisms against the sole member to clamp the margin thereof and the margins of the upper between said mechanisms and said anvils and then to cause said mechanisms to drive the fastenings into said margins while the latter are thus clamped.

12. A machine for use in the manufacture of stitchdown shoes having, in combination, a support for a last having an upper and a sole member mounted thereon with the sole member projecting beyond the last bottom, grippers at the opposite sides of the support for gripping the opposite margins of the upper and holding them in an outturned position above the projecting sole member, means for effecting relative movement of the support and grippers heightwise of the last to pull the upper over the last with the outturned margins of the upper overlying the projecting margin of the sole member, fastening inserting mechanisms at opposite sides of the support for inserting fastenings through the projecting margins of the sole member and the mar-

gins of the upper to hold the upper in pulled-over position relatively to the last, means for actuating each fastening inserting mechanism including a lever, a spring for operating said lever, a latch for locking the lever in retracted position, and rotatable means constructed and arranged to increase the tension of the spring and then to release the latch to permit said lever to actuate the inserting mechanism under the increased tension of the spring.

13. A machine for use in the manufacture of stitchdown shoes having, in combination, a support for receiving a last having an upper and a sole member mounted thereon with the sole member projecting beyond the last bottom, grippers at opposite sides of said support adjacent to the toe portion of the last for gripping the opposite margins of the upper and holding them in an outturned position above the projecting sole member, means for effecting relative movement of the support and grippers heightwise and lengthwise of the last to pull the upper over the last with the outturned margins of the upper overlying the projecting sole member, fastening inserting mechanisms at opposite sides of the support for inserting metallic fastenings through the sole member and the outturned upper to secure the upper in pulled-over relation to the last, anvils cooperating with said inserting mechanisms for clinching the fastenings after they have been inserted, manually operated means for actuating each fastening inserting mechanism comprising a driving lever, a spring for operating said lever, a latch for said lever, and a rotatable member operable first to tighten the spring and then to trip the latch and release said lever to actuate the fastening inserting mechanism, said rotatable member also operating to swing the fastening inserting mechanism into engagement with the projecting sole member to clamp it and the upper between said mechanism and the anvil before the fastening is inserted.

14. A machine for use in the manufacture of stitchdown shoes having, in combination, a support for a last having an upper and a sole member mounted thereon with the sole member projecting beyond the last bottom, grippers at opposite sides of said support at the forepart of the last for gripping the opposite margins of the upper and holding them in an outturned position above the projecting sole member, means for effecting movement of the shoe support relatively to the grippers heightwise of the last to pull the upper over the last with the outturned margins of the upper overlying the projecting sole member, fastening inserting mechanisms at opposite sides of the support for inserting fastenings through the projecting margins of the sole member and upper to secure the upper in pulled-over relation to the last, said mechanisms being constructed and arranged to insert the fastenings into the lower surface of the sole member and upwardly through the margins of the sole member and upper, anvils for clinching said fastenings against the outer surface of the upper margins, means for actuating each fastening inserting mechanism comprising a spring-operated lever, a latch therefor, a rotary member operable to release said latch to permit the lever to operate, and means operated by rotation of said rotary member for swinging the fastening inserting mechanism positively into engagement with the sole member before the fastening is inserted.

15. A machine for use in the manufacture of stitchdown shoes having, in combination, a sup-

port for a last having an upper and a sole member mounted thereon with the sole member projecting beyond the last bottom, grippers at opposite sides of the support at the forepart of the last for gripping the opposite margins of the upper and holding them in an outturned position over the projecting sole member, means for effecting relative movement of the support and grippers heightwise of the last to cause the upper to be pulled over the last with its opposite margins overlying the projecting sole member, fastening inserting mechanisms at opposite sides of the support for inserting fastenings simultaneously through the margins of the sole member and upper at opposite sides of the last to secure the upper in pulled-over position on the last, said mechanisms being carried by fastening supplying members pivoted for swinging movement heightwise of the support about horizontal pivots located substantial distances away from said support, means carried by said supplying members for feeding the fastenings to the inserting mechanisms, and means for actuating each fastening inserting mechanism including a rotary member arranged first to swing said supplying member upwardly to move the inserting mechanism into engagement with the sole member and then to actuate the fastening inserting mechanism to drive the fastening.

16. A machine for use in the manufacture of shoes having, in combination, a support for a last having an upper and a sole member mounted thereon, said sole member extending beyond the last bottom, means including gripping mechanisms at opposite sides of the support for pulling the upper over the last on said support, mechanism for inserting metallic fastenings through the sole member and upper at opposite sides of the last and located outwardly of the edge of the last bottom to hold the upper in pulled-over position thereon, and means for moving the opposite sides of the upper inwardly toward the support to press the upper against the sides of the last before the fastenings are inserted.

17. A machine for use in the manufacture of shoes having, in combination, a support for a last having an upper and a sole member mounted thereon, means including gripping mechanisms at opposite sides of the support at the forepart of the last for pulling the upper over the last with the opposite margins of the upper turned outwardly, means for moving the opposite side portions of the upper yielding toward the support to press the upper against the last, and mechanisms for inserting staples through the sole member and the outturned margins of the upper at opposite sides of the last to secure the upper in pulled-over position on the last.

18. A machine for use in the manufacture of shoes having, in combination, a support for a last having an upper and a sole member mounted thereon, said sole member projecting beyond the bottom surface of the last, gripping mechanisms at opposite sides of the support for gripping the upper, means for effecting relative movement of the support and gripping mechanisms heightwise of the last to pull the upper over the last, mechanisms for inserting metallic fastenings through the projecting sole member and upper margins at opposite sides of the last with the fastenings located outwardly of the edge of the last bottom to hold the upper in pulled-over relation to the last, means for moving the opposite sides of the upper inwardly toward the support to press the side portions of the upper against

the sides of the last, and means for operating said last-named means before the fastening inserting mechanisms are operated so that the side portions of the upper will be pressed against the last when the fastenings are inserted.

19. A machine for use in the manufacture of shoes having, in combination, a support for a last having an upper and a sole member mounted thereon, the margin of the sole member projecting beyond the bottom of the last, mechanisms for gripping the opposite margins of the upper and holding them in an outturned position over the projecting margin of the sole member, means for effecting relative movement of the support and gripping mechanisms to pull the upper over the last with the outturned margins of the upper overlying the projecting margin of the sole member, means for clamping said outturned margins flat against the margin of the sole member, mechanism for inserting metallic fastenings through the margins of said sole member and upper to secure the upper in pulled-over position on the last, and means for moving the clamped margins inwardly toward the support to press the upper against the sides of the last before the fastenings are inserted, said last-named means being arranged to operate yieldingly during the pressing action.

20. A machine for use in the manufacture of shoes having, in combination, a support for a last having an upper and a sole member mounted thereon, gripping mechanisms at opposite sides of the support at the forepart of the last for gripping the opposite side portions of the upper, means for effecting relative movement of the support and gripping mechanisms to pull the upper over the last, mechanisms for inserting fastenings through the sole member and upper at opposite sides of the last to secure the upper in pulled-over position thereon, means for actuating the fastening inserting mechanisms, and means actuated by operation of said actuating means for moving the opposite side portions of the upper inwardly toward the support to press said portions against the sides of the last.

21. A machine for use in the manufacture of shoes having, in combination, a support for a last having an upper and a sole member mounted thereon, gripping mechanisms at opposite sides of the support for gripping the opposite sides of the upper, means for effecting relative movement of the support and gripping mechanisms heightwise and lengthwise of the last to pull the upper over the last, mechanisms for inserting fastenings through the sole member and upper at opposite sides of the last to secure the upper in pulled-over position thereon, means for actuating said fastening inserting mechanisms, and means actuated automatically by operation of said last-named means for moving the opposite side portions of the upper yieldingly toward the shoe support to press said side portions inwardly against the opposite sides of the last before the fastenings are inserted.

22. A machine for use in the manufacture of shoes having, in combination, a support for a last having an upper and a sole member mounted thereon, mechanisms for gripping the upper at opposite sides of the support, means for effecting relative movement of the support and gripping mechanisms heightwise of the last to pull the upper over the last, mechanisms for inserting metallic fastenings through the sole member and upper at opposite sides of the last to secure the upper in pulled-over position thereon, and means

for moving the opposite side portions of the upper inwardly toward the support to press the upper against the sides of the last before the fastenings are inserted, said last-named means operating automatically and having a predetermined operative stroke but being arranged to act yieldingly during the pressing movement.

23. A machine for use in the manufacture of shoes having, in combination, a support for a last having an upper and a sole member mounted thereon, upper gripping mechanisms at opposite sides of the support at the forepart of the last, means for effecting relative movement of the support and gripping mechanisms heightwise of the last to pull the upper over the last, mechanisms for inserting fastenings through the sole member and upper at opposite sides of the last to secure the upper in pulled-over position thereon, and means for automatically moving the opposite sides of the upper yieldingly toward the last to press the upper against the sides thereof before the fastenings are inserted, said last-named means including upper clamping members, cams for operating said members, a cam for moving said members automatically toward the last, and springs for permitting said clamping members to yield as they move against the last.

24. A machine for use in the manufacture of shoes having, in combination, a support for a last having an upper and a sole member mounted thereon, upper gripping mechanisms at opposite sides of the support at the forepart of the last, means for effecting relative movement of the support and gripping mechanisms heightwise and lengthwise of the last to pull the upper over the last, means for clamping the sole member and upper to maintain the upper in pulled-over position on the last, mechanism for inserting fastenings through the sole member and upper at opposite sides of the last to secure the upper in pulled-over position thereon, and means for automatically moving said clamping means yieldingly toward the last prior to the insertion of said fastenings to press the upper against the sides of the last before it is secured in pulled-over position, said automatic means comprising a pivoted lever provided with a cam slot, means for swinging said lever about its pivot, and connections between said pivoted lever and said clamping means for causing the latter to move inwardly toward the support with a yielding action when said lever is swung about its pivot, said connections including a roll in said cam slot and springs for transmitting the positive movement of the roll to said clamping means.

25. A machine for use in the manufacture of shoes having, in combination, a support for a last having an upper and a sole member mounted thereon, upper gripping mechanisms at opposite sides of the support at the forepart of the last for gripping the opposite sides of the upper, means for effecting relative movement of the support and gripping mechanisms heightwise of the last to pull the upper over the last, mechanisms for inserting metallic fastenings through the sole member and upper at opposite sides of said forepart to secure the upper in pulled-over position on the last, means for actuating the fastening inserting mechanisms, means for pressing the opposite sides of the upper yieldingly against the sides of the last before the fastenings are inserted, and means actuated by operation of said actuating means for operating said pressing means, said last-named means in-

cluding a lever having a cam slot therein, a pair of levers at opposite sides of the support arranged to be swung inwardly by connections to said cam slot, and springs between said pair of levers and said pressing means for moving the latter yieldingly toward the last.

26. A machine for use in the manufacture of shoes having, in combination, a support for a last having an upper and a sole member mounted thereon, upper gripping mechanisms at opposite sides of the support, anvils engaging the upper adjacent to said gripping mechanisms, means for effecting relative movement of the support and gripping mechanisms heightwise of the last to pull the upper over the last, fastening inserting mechanisms at opposite sides of the support arranged for swinging movement heightwise of the support toward and away from said anvils, means for actuating said fastening inserting mechanisms, said actuating means being arranged to swing said fastening inserting mechanisms into engagement with the sole member to clamp it and the upper between said mechanisms and the stationary anvils, and means for moving said fastening inserting mechanisms and said anvils yieldingly toward the support while in clamping relation with the sole member and upper to press the upper against the sides of the last before the fastenings are inserted.

27. A machine for use in the manufacture of shoes having, in combination, a support for a last having an upper and a sole member mounted thereon with the sole member extending beyond the last bottom, mechanisms for gripping the upper at opposite sides of the support and holding it in an outturned position, means for effecting relative movement of the support and gripping mechanisms to pull the upper over the last and position it against the sole extension, mechanisms for inserting metallic fastenings through the sole member and upper at opposite sides of the last and located outwardly of its bottom surface to secure the upper in pulled-over position thereon, and means for adjusting said gripping and fastening inserting mechanisms relatively to the support to adapt them for operating upon shoes of different styles and sizes.

28. A machine for use in the manufacture of shoes having, in combination, a support for a last having an upper and a sole member mounted thereon, mechanisms for gripping the upper at opposite sides of the support, means for effecting relative movement of the support and gripping mechanisms to pull the upper over the last, mechanisms for inserting fastenings through the sole member and upper at opposite sides of the last to secure the upper in pulled-over position thereon, single means for adjusting the opposite gripping and fastening inserting mechanisms laterally toward or away from the support simultaneously to adapt them for operating upon shoes of different sizes, and means for varying the angular positions of said mechanisms relatively to the support to accommodate shoes of different styles.

29. A machine for use in the manufacture of shoes having, in combination, a shoe support for a last having an upper and a sole member mounted thereon, mechanism for gripping the upper at opposite sides of the support at the forepart of the last, means for effecting relative movement of the support and gripping mechanisms heightwise of the last to pull the upper over the last, mechanisms at opposite sides of the support for

inserting fastenings to secure the upper in pulled-over position on the last, single means for simultaneously adjusting the gripping and fastening inserting mechanisms at opposite sides of the support widthwise toward or away from said support to adapt said mechanisms for operating upon shoes of different styles and sizes, and means individual to the gripping and fastening inserting mechanisms at opposite sides of the support for adjusting said mechanisms independently of those at the other side of said support to vary the angular position of said mechanisms relatively to the support.

30. A machine for use in the manufacture of shoes having, in combination, a support for a last having an upper and a sole member mounted thereon, mechanisms for gripping the upper at opposite sides of the support at the forepart of the last, mechanisms at opposite sides of the support for inserting fastenings through the sole member and upper, carrier members for said gripping mechanisms and fastening inserting mechanisms, means for adjusting said carrier members toward or away from the support to adapt the gripping and fastening inserting mechanisms at opposite sides of the support for operating upon shoes of different styles and sizes, and means for swinging said carrier members laterally of the support about vertical pivots to vary the angular positions of said mechanisms in accordance with the styles of the different shoes operated upon.

31. A machine for use in the manufacture of shoes having, in combination, a support for a last having an upper and a sole member mounted thereon, mechanisms for gripping the upper at opposite sides of the support at the forepart of the last, mechanisms at opposite sides of the support for inserting fastenings through the sole member and upper, carrier members for holding said gripping and said fastening inserting mechanisms, means for supporting the carrier members for swinging movement lengthwise of the last support about vertical axes, and means for moving the supporting means toward and away from the last support to position the carrier members and the gripping and fastening inserting mechanisms in the proper widthwise positions for shoes of different styles and sizes.

32. A machine for use in the manufacture of shoes having, in combination, a support for a last having an upper and a sole member mounted thereon, mechanisms for gripping the upper at opposite sides of the support at the forepart of the last, mechanisms at opposite sides of the support for inserting fastenings through the sole member and upper, carrier members for said gripping and fastening inserting mechanisms, said carrier members being arranged for adjustment transversely of the support toward and away from the shoe thereon and also for swinging movement laterally of the support, single means for simultaneously adjusting said carrier members toward or away from the support to adapt the gripping and fastening inserting mechanisms for operating upon shoes of different styles and sizes, and manually operated means for positioning said members separately in different angles relatively to the support to position said mechanisms for shoes of different styles.

33. A machine for use in the manufacture of shoes having, in combination, a support for a last having an upper and a sole member mounted thereon, mechanisms for gripping the upper at opposite sides of the support at the forepart

of the last, mechanisms at opposite sides of the support for inserting fastenings through the sole member and upper, carrier members for said gripping and fastening inserting mechanisms, swinging members for holding said carrier members, said swinging members being arranged for movement toward and away from the support about vertical axes, a screw having threaded portions thereon for simultaneously adjusting said swinging members toward or away from the support, and separate means for adjusting each carrier member angularly with respect to its swinging member to vary the angular position of the carrier member relatively to the support.

34. A machine for use in the manufacture of shoes having, in combination, a support for a last having an upper and a sole member mounted thereon, mechanisms for gripping the upper at opposite sides of the support, means for adjusting said gripping mechanisms simultaneously toward or away from the support to position them for operating upon shoes of different styles and sizes, means for effecting heightwise movement of the support relatively to the gripping mechanisms to pull the upper over the last, and means for operating said adjusting means automatically to move the gripping mechanisms inwardly toward the support to cause said gripping mechanisms to press the upper yieldingly against the sides of the last after the upper has been pulled over the last.

35. A machine for use in the manufacture of shoes having, in combination, a support for a last having an upper and a sole member mounted thereon, mechanisms at opposite sides of the support for gripping the upper at the opposite sides of the last, means including a right- and left-hand threaded screw for adjusting said gripping mechanisms toward and away from the support, means for effecting relative movement of the support and gripping mechanisms to pull the upper over the last, and means including a pivoted lever having a cam slot therein for operating said adjusting means independently of the operation of said screw to cause the gripping mechanisms to move inwardly toward the support to press the upper yieldingly against the sides of the last after the upper has been pulled over.

36. A machine for use in the manufacture of shoes having, in combination, a support for a last having an upper and a sole member mounted thereon, grippers at opposite sides of the support at the forepart of the last for gripping the upper at opposite sides of said last, means for clamping the upper adjacent to the grippers, mechanisms for adjusting said grippers and said clamping means toward and away from the support to position them for operating upon shoes of different sizes, said mechanisms including levers arranged for swinging movement about pivots located intermediately of their opposite ends, a single screw for moving said levers about their pivots to accomplish the adjustments simultaneously, said levers being also pivotally connected to said screw, and means for automatically actuating said levers independently of the operation of said screw to move the grippers and clamping means inwardly toward the support irrespective of their adjusted positions to press the upper against the sides of the last, said last-named means causing said levers to swing this time about the pivots connecting them to said screw.

37. A machine for use in the manufacture of

shoes having, in combination, a support for a last having an upper and a sole member mounted thereon, grippers at opposite sides of the support at the forepart of the last for gripping the opposite margins of the upper, toggle mechanisms for operating said grippers, means for effecting relative movement of the support and grippers heightwise of the last to pull the upper over the last, mechanisms at opposite sides of the support for inserting metallic fastenings through the sole member and upper to hold the upper in pulled-over position on the last, means for operating the fastening inserting mechanisms to insert the fastenings, and means for automatically breaking said toggle mechanisms and releasing the grippers before the fastenings are inserted.

38. A machine for use in the manufacture of shoes having, in combination, a support for a last having an upper and a sole member mounted thereon, grippers at opposite sides of the support at the forepart of the last for gripping the opposite margins of the upper, means for closing said grippers and locking them in closed position, said means including toggle mechanisms and a latch therefor, means for effecting relative movement of the support and grippers heightwise of the last to pull the upper over the last, mechanisms at opposite sides of the support for inserting fastenings through the sole member and upper to secure the upper in pulled-over position on the last, means for actuating said fastening inserting mechanisms, and means actuated automatically by the operation of said actuating means for releasing said latch and breaking the gripper closing toggles and thereby unlocking the grippers.

39. A machine for use in the manufacture of shoes having, in combination, a support for a last having an upper and a sole member mounted thereon, grippers at opposite sides of the support at the forepart of the last for gripping the margins of the upper at opposite sides of the last, means for effecting relative movement of the support and grippers heightwise of the last to pull the upper over the last, mechanisms at opposite sides of the support for inserting fastenings to secure the upper in pulled-over position on the last, means for moving the opposite side portions of the upper inwardly toward the support before the fastenings are inserted to press the upper yieldingly against the sides of the last, and means for releasing the grippers before the upper is moved inwardly.

40. A machine for use in the manufacture of shoes having, in combination, a support for a last having an upper and a sole member mounted thereon, grippers at opposite sides of the support at the forepart of the last for gripping the opposite margins of the upper, means for effecting relative movement of the support and grippers heightwise of the last to pull the upper over the last, means for clamping the opposite margins of the upper against the sole member, means for moving the clamping means inwardly toward the support to press the upper yieldingly against the sides of the last after it has been pulled over, and means for releasing the grippers before said clamping means is moved inwardly.

41. A machine for use in the manufacture of shoes having, in combination, a support for a last having an upper and a sole member mounted thereon, grippers at opposite sides of the support at the forepart of the last for gripping the opposite margins of the upper, means for effecting relative movement of the support and grippers

heightwise and lengthwise of the last to pull the upper over the last, mechanisms at opposite sides of the support for inserting metallic fastenings through the sole member and upper margins at opposite sides of the last to secure the upper in pulled-over position thereon, anvils associated with said fastening inserting mechanisms for clinching the metal fastenings against the surface of the upper, means for causing relative movement of the fastening inserting mechanisms and anvils to clamp the sole member and upper between said mechanisms and said anvils, and means for automatically releasing the grippers after the sole member and upper margins have been thus clamped.

42. A machine for use in the manufacture of stitchdown shoes having, in combination, a support for a last having an upper and a sole member mounted thereon, said sole member projecting beyond the periphery of the last bottom and the marginal portion of the upper extending over the projecting sole member, grippers at opposite sides of the support for gripping the opposite margins of the upper and holding them in an outturned position over said sole member, means for effecting relative movement of the support and grippers heightwise of the last to pull the upper over the last with the margins of the upper positioned flat against the projecting sole member, mechanisms at opposite sides of the support for inserting fastenings through the sole member and upper at opposite sides of the last to secure the upper in pulled-over position on the

last, and means for releasing the grippers before the fastenings are inserted.

43. A machine for use in the manufacture of stitchdown shoes having, in combination, a support for a last having an upper and a sole member mounted thereon, said sole member projecting beyond the periphery of the last bottom and the marginal portion of the upper extending over the projecting sole member, grippers at opposite sides of the support at the forepart of the last for gripping the opposite margins of the upper and holding them in an outturned position overlying said sole member, means for effecting relative movement of the support and grippers heightwise of the last to pull the upper over the last with the margins of the upper positioned against said projecting sole member, mechanisms at opposite sides of the support for inserting fastenings through the projecting sole member and the upper margins to secure the upper in pulled-over position thereon, means for clamping said sole member and upper margins against each other, means for moving the clamping means inwardly toward the support to press the upper yieldingly against the sides of the last before the fastenings are inserted, means for actuating said fastening inserting mechanisms, and means actuated by the operation of said actuating means for releasing the grippers before the clamping means is moved inwardly.
